UNITED STATES PATENT OFFICE

131,258

DESIGN FOR A FRAME FOR A DISPLAY BOARD OR THE LIKE

John Bascom Dey, Lynchburg, Va.

Application May 22, 1941, Serial No. 101,098

Term of patent 14 years

To all whom it may concern:

Be it known that I, John Bascom Dey, a citizen of the United States, residing in Lynchburg, in the county of Campbell and State of Virginia, have invented a new, original, and ornamental Design for a Frame for a Display Board or the like, of which the following is a specification, reference being had to the accompanying drawing, forming part thereof, in which:

Figure 1 is a front elevational view of a frame for a display board or the like, showing my new design;

Figure 2 is a horizontal sectional view thereof, taken on line 2—2 of Figure 1.

Figure 3 is a vertical sectional view thereof, taken on line 3—3 of Figure 1;

Figure 4 is a vertical sectional view of the frame for a display board or the like, taken on line 4—4 of Figure 1; and

Figure 5 is an enlarged contour sectional view of the frame for a display board or the like.

I claim:

The ornamental design for a frame for a display board or the like, substantially as shown.

JOHN BASCOM DEY.
